ATTORNEYS

UNITED STATES PATENT OFFICE.

JOSEPH H. HARPER, OF SPRINGFIELD, OHIO.

COFFIN.

1,423,848.

Specification of Letters Patent. Patented July 25, 1922.

Application filed January 27, 1921. Serial No. 440,433.

To all whom it may concern:

Be it known that I, JOSEPH H. HARPER, a citizen of the United States, residing at Springfield, in the county of Clark and State of Ohio, have invented certain new and useful Improvements in Coffins, of which the following is a specification, reference being had therein to the accompanying drawing.

My invention relates to coffins and in particular to the sealing of the coffin top.

The object of my invention is to provide a coffin which may be economically made out of light and cheap material, preferably of metal, as a hermetically sealed casket.

It is the object of my invention to provide such a casket which will exclude light, air and moisture. It is also an object of my invention to provide a construction for sealing the casket or coffin which will be rigid, positive in its action and simple to manufacture, as well as simple to operate.

Referring to the drawings:

Fig. 1 is a section on the transverse axis of a coffin showing the method of sealing the coffin and the reinforcing construction;

Fig. 2 is a section of a portion of the coffin on its longitudinal axis showing a portion of the reinforcing members; and

Fig. 3 is an enlarged view of the sealing mechanism.

1 refers to the bottom of the coffin, 2 to the vertical side which is a part of the bottom, both members being of one piece. This side 2 is projected at 3 at right angles for a short distance and then upwardly at 4 where it is turned over on itself and descends downwardly at 5 and then at right angles to the downwardly extending portion, as at 6. On the inside of the coffin is a transverse brace 7 and a vertical brace 8. On the outside of the coffin is a one-piece member having a bottom strap 9 and a continuation of the bottom at right angles thereto for the sides forming a side strap 10. To the side strap 10 is fastened a handle 11 to be used for lifting the coffin or casket. There is a reinforcing side band 12 directly beneath the handle 11 and the side strap 10, between the side strap 10 and the side wall 2. Beneath the laterally extending members 3 and 6 of the side wall is a reinforcing plate 13 held to this horizontally extending side wall and the horizontally extending top flange to be described later, by bolts or screws 14 of any desired character.

The top is composed of two members 15

and 16. The top member 15 descends at its edges downwardly, as at 16, to a point approximately on the level of the top of the sides of the coffin when it is extended at 60 right angles outwardly at 17 and is then turned over upon itself and brought inwardly, as at 18, until it reaches the point at which it was bent at right angles outwardly, when it is bent upwardly to follow on the 65 inside its own upwardly extending wall, as at 19, for approximately half the distance of its descending outer side of the top. It is then turned over the upwardly extending portion of the side walls 4 and 5 and is bent 70 downwardly around that upwardly extending portion, as at 20, to form a shoulder, the end of which abuts against the brace 8. The inner wall of the top 16 follows the outer wall until its sides start their downward movement when it moves inwardly at 22 and downwardly adjacent to 20 at 23. It then turns in a right angle following 20 and 21 and downwardly at 24 on the innermost side of the upstanding brace 8 which is 80 an angle iron having one member parallel to the side of the coffin as at 25, and the other extending out into the coffin, as at 26.

It will be observed that the result of this is that there is a number of surfaces brought 85 in wedging contact with one another which when fastened together by a single bolt or screw will form a rigid interlocking and positive connection that is absolutely air tight, water tight and light tight, as well as 90 impervious to the entrance of any other agency.

While I have shown and described certain features as constituting my invention, it will be understood that parts have been shown 95 for purposes of illustration only, and that I do not desire to be limited to such details, as obvious modifications will occur to a person skilled in the art.

Having thus fully described my invention, 100 what I claim as new and desire to secure by Letters Patent, is:—

1. In a coffin, a bottom and sides, said sides being projected at their upper edges laterally, upwardly, downwardly and outwardly, a brace adjacent either of the sides projecting above the lateral projection of the side, a top composed of an inner and outer wall adapted to embrace between their lower edges the upwardly projecting portion of the sides and the internal brace. 110

2. In a coffin, a bottom and sides, said

sides being projected at their upper edges laterally, upwardly, downwardly and outwardly; a brace adjacent either of the sides projecting above the lateral projection of 5 the side, a top composed of an inner and outer wall adapted to embrace between their lower edges the upwardly projecting portion of the sides and the internal brace, and positive means for fastening said top members and sides to one another.

3. In a coffin, a bottom and sides, said sides being projected at their upper edges laterally, upwardly, downwardly and outwardly, a brace adjacent either of the sides 15 projecting above the lateral projection of the side, a top composed of an inner and outer wall adapted to embrace between their lower edges the upwardly projecting portion of the sides and the internal brace, a 20 reinforcing means adjacent the point of union of the top members and the sides, and means for positively fastening together said top, sides and reinforcing means.

4. In a coffin, a one piece bottom and side 25 structure, reinforcing members within said coffin adjacent the bottom and sides thereof, reinforcing members without said coffin adjacent the bottom and sides, a top, and means of interlocking said sides, top and reinforcing means in a unit structure.

5. In a coffin, a bottom and sides projected laterally at the top, upwardly, downwardly parallel to the upward projection and outwardly; braces adjacent the sides 35 projecting slightly above the top thereof, each of said braces having one portion adjacent the sides and the other portion extending at right angles thereto; a two piece top consisting of an outer wall bent down- 40 wardly on the edge, outwardly at right angles thereto in a plane parallel to the top, folded inwardly parallel to itself and to the outwardly extending outer edge of the side wall, upwardly parallel to the upper projection of the side wall, downwardly parallel to the upper projection of the side wall and inwardly to the inside of the side wall 45 closely adjacent to the corresponding configuration of the upper edge of the side wall 50 wall with its end abutting the parallel portion of the side wall brace; an inner wall of the two piece top parallel to the outer wall on its top, extending downwardly and divergently from the downwardly extending portion of the outer wall, embracing the innermost downwardly extending and inwardly extending portion of the outer wall and embracing at its lower end with an inwardly extending and downwardly project- 55 ing portion, the upstanding brace within the side wall locking between it the side wall and the inwardly projecting outer wall this 60 upstanding brace.

6. In a coffin, a bottom and sides project- 65 ed laterally at the top, upwardly, down-

wardly parallel to the upward projection and outwardly; braces adjacent the sides projecting slightly above the top thereof, each of said braces having one portion adjacent the sides and the other portion extending at right angles thereto in a plane parallel to the top, folded inwardly parallel to itself and to the outwardly extending outer edge of the side wall, upwardly parallel to the upper projection of the side wall, downwardly parallel to the upper projection of the side wall and inwardly to the inside of the side wall closely adjacent to the corresponding configuration of the upper edge of the side wall with its end abutting the parallel portion of the side wall brace; an inner wall of the two piece top parallel to the outer wall on its top, extending downwardly and divergently from the downwardly extending portion of the outer wall, embracing the innermost downwardly extending and inwardly extending portion of the outer wall and embracing at its lower end with an inwardly extending and downwardly projecting portion, the upstanding brace within the side wall locking between it the side wall and the inwardly projecting outer wall this upstanding brace, a reinforcing plate beneath the outwardly projecting top member and side wall member, and means of fastening positively said side wall member, outer top member and reinforcing member one to another.

7. In a coffin, a bottom and sides projected laterally at the top, upwardly, downwardly parallel to the upward projection and outwardly; braces adjacent the sides projecting slightly above the top thereof, each of said braces having one portion adjacent the sides and the other portion extending at right angles thereto; a two piece top consisting of an outer wall bent downwardly on the edge, outwardly at right angles thereto in a plane parallel to the top, folded inwardly parallel to itself and to the outwardly extending outer edge of the side wall, upwardly parallel to the upper projection of the side wall, downwardly parallel to the upper projection of the side wall and inwardly to the inside of the side wall closely adjacent to the corresponding configuration of the upper edge of the side wall with its end abutting the parallel portion of the side wall brace, an inner wall of the two piece top parallel to the outer wall on its top, extending downwardly and divergently from the downwardly extending portion of the outer wall, embracing the innermost downwardly extending and inwardly extending portion of the outer wall and embracing at its lower end with an inwardly extending and downwardly projecting portion, the upstanding brace within the side wall locking between it the side wall and the inwardly projecting outer wall this upstanding brace.

side wall locking between it the side wall and the inwardly projecting outer wall this upstanding brace, a reinforcing plate beneath the outwardly projecting top member 5 and side wall member, means of fastening positively said side wall member, outer top member and reinforcing member one to another, and reinforcing straps on the outside of the bottom and sides of said coffin with 10 handles affixed thereto.

8. In a coffin, a bottom and sides projected laterally at the top, upwardly, downwardly parallel to the upward projection and outwardly; braces adjacent the sides projecting 15 slightly above the top thereof, each of said braces having one portion adjacent the sides and the other portion extending at right angles thereto; a two piece top consisting of an outer wall bent downwardly on the edge, outwardly at right angles thereto in a plane 20 parallel to the top, folded inwardly parallel to itself and to the outwardly extending outer edge of the side wall, upwardly parallel to the upper projection of the side wall, 25 downwardly parallel to the upper projection of the side wall and inwardly to the inside of the side wall closely adjacent to the corresponding configuration of the upper edge of the side wall with its end abutting 30 the parallel portion of the side wall brace, an inner wall of the two piece top parallel to the outer wall on its top extending downwardly and divergently from the downwardly extending portion of the outer wall, em-

bracing the innermost downwardly extending and inwardly extending portion of the outer wall and embracing at its lower end with an inwardly extending and downwardly projecting portion, the upstanding brace within the side wall locking between it, the 35 side wall and the inwardly projecting outer wall this upstanding brace, a reinforcing plate beneath the outwardly projecting top member and side wall member, means of fastening positively said side wall member, 40 outer top member and reinforcing member one to another, reinforcing straps on the outside of the bottom and sides of said coffin with handles affixed thereto, and laterally reinforcing straps beneath the handles on 45 the outside of said side walls locked between the upwardly extending straps and the side walls.

9. In a coffin, a one piece bottom and side structure, the sides whereof are projected at 50 their upper edges laterally, upwardly, downwardly outwardly, and a top composed of an inner and outer wall adapted to embrace between their lower edges the upwardly projecting portion of the sides, a reinforcing 55 plate beneath the outwardly projecting top member and the side wall member, and means of fastening positively said side wall members, the outer top member and reinforcing member one to another. 60

In testimony whereof, I affix my signature.

JOSEPH H. HARPER.
